CLAIM

The ornamental design for a keratoprosthesis for corneal replacement as shown and described.

DESCRIPTION

FIG. 1 is a first perspective view showing a new design for a keratoprosthesis for corneal replacement;

FIG. 2 is a second perspective view showing the new design of FIG. 1;

FIG. 3 is a front view showing the new design of FIG. 1; FIG. 4 is a back view showing the new design of FIG. 1; FIG. 5 is a right-side view showing the new design of FIG. 1;

FIG. 6 is a left-side view showing the new design of FIG. 1; FIG. 7 is a top view showing the new design of FIG. 1; and, FIG. 8 is a bottom view showing the new design of FIG. 1.

1 Claim, 8 Drawing Sheets
